STOKER CONSTRUCTION

Royce L. Beers, Detroit, Mich., assignor to Detroit Stoker Company, Detroit, Mich., a corporation of Michigan

Application April 3, 1934, Serial No. 718,834

9 Claims. (Cl. 110—101)

This invention relates generally to stokers, especially to those of the sprinkler type, and consists of certain novel details of construction, combinations and arrangements of parts, that will be hereinafter more fully described and particularly pointed out in the appended claims.

One of the essential objects of the invention is to provide an improved apron tuyère and wear plate assembly.

Another object is to provide an assembly of this type wherein the wear plate straddles and protects the lower edge of a fuel feed opening in a casting carried by an upright plate upon the front wall of the furnace.

Another object is to provide an assembly wherein the apron tuyères have upper and lower portions joined together at their rear ends and extending toward and cooperating with the wear plate and upright plate aforesaid to form a windbox or air chamber.

Another object is to provide an assembly wherein the upper portions of the apron tuyères extend rearward from the wear plate and the lower portions of said tuyères are provided upon their underside with a high temperature heat resisting substance.

Another object is to provide an assembly wherein the means for supporting the apron tuyères preferably comprises means on the upright plate holding in juxtaposition a portion of the wear plate and the upper portions of the apron tuyères.

Other objects, advantages and novel details of construction of this invention will be made more apparent as this description proceeds, especially when considered in connection with the accompanying drawings, wherein:

Figure 1 is a fragmentary vertical sectional view through a stoker construction embodying my invention in a plane adjacent to one end thereof;

Figure 2 is a front elevation of the wear plate; Figure 3 is a sectional view taken on the line 3—3 of Figure 2;

Figure 4 is a side elevation of one of the apron tuyères with the refractory material shown in section;

Figure 5 is an end elevation of the tuyère illustrated in Figure 4;

Figure 6 is a sectional view taken on the line 6—6 of Figure 4.

Referring now to the drawings, A is an upright plate adapted to be secured upon the front wall of a furnace and having a substantially rectangular fuel feed opening 1 therein, and B is a substantially rectangular base plate mounted upon the outer side of the upright plate A and having a substantially rectangular opening 2 therein registering with the opening 1. Preferably the base plate B is a casting and has a shoulder 2^a which projects rearwardly over the lower edge 1^a of the

opening 1 in the plate A. C is a rotor in front of said casting B opposite the lower edge 3 of the opening 2 and provided with suitable blades D for projecting fuel rearwardly through said opening into the furnace. E is a hopper for the fuel; F is a distributor plate beneath said hopper and adjustable over an edge 4 of the rotor housing G; and H is a ram for pushing onto the rotor C the fuel that is received on the plate F from the hopper E.

J is the wear plate and K are the apron tuyères embodying my invention. As shown, the wear plate J extends lengthwise of and straddles the lower edge 3 of the fuel feed opening 2 in the casting B. The front depending portion 5 of said plate is substantially flush with the front face 6 of the casting and has interlocking engagement with the latter, while the rear depending portion 7 is upon and substantially flat against the rear face of said casting. Preferably the intermediate top 8 of the wear plate inclines downwardly and rearwardly from the front portion 5 to the rear portion 7.

The apron tuyères K project rearwardly from the wear plate J and are preferably supported from a bracket L fastened to the front plate A. Any suitable means such as the bolts 12^a and nuts 12^b may be employed for fastening the bracket L to the plate A. Preferably the tuyères K of the apron are arranged side by side and are alike in construction. As shown, each tuyère K has a body M of cast iron and a protecting covering N on the underside thereof of high temperature heat resisting cement. The upper portion 10 of each tuyère body has a hook-shaped portion 11 disposed on the bracket L between an upstanding portion 12 thereof and the rear depending portion 7 of the wear plate and is inclined downwardly and rearwardly approximately in alignment with the inclined top 8 of the wear plate. The lower portion 13 of each tuyère body M has a relatively wide and thick web 14 that extends downwardly from the upper portion 10 at its lower end, thence forward and terminates in a depending portion 15 which abuts the rear face of a depending portion 16 of the bracket and has a forwardly offset portion 18 bearing against the rear face of the bracket on the plate A. Projecting downwardly from the upper portion 10 at the lower end thereof, thence forwardly to the depending portion 15 at the upper end of the offset portion 18 is a longitudinally extending web 19 of less width than the web 14. Located between and connected to the webs 14 and 19 is a longitudinally extending upright web 20, while disposed upon opposite sides of this web between and at spaced points of the webs 14 and 19 are transversely extending ribs 22. The cement N envelopes and is suspended from the webs 19 and 20 and ribs 22 between the lower end of

the upper portion 10 and the depending portion 15 of the lower portion. Preferably the lower face 23 of this cement is flush with the lower end 24 of the offset portion 18 and curves upwardly to 5 and is substantially flush with the rear face 25 of the upper portion 10. To insure a firm bond between the parts, the web 20 is preferably apertured upon opposite sides of the ribs 22 to receive portions of the cement. Preferably 10 suitable slots 26 for the passage of air are provided in the upper portion 10. Likewise, recesses or notches 28 and 29 respectively are provided in the upper portion 10 and cement N at opposite sides thereof for the passage of air. In 15 fact, the tuyères are constructed and arranged in such a way that they cooperate with the upright plate A and wear plate J to form a windbox or air chamber.

What I claim as my invention is:

20 1. In a stoker, an upright plate adapted to be secured upon the front wall of a furnace and having a fuel feed opening therein, a base plate mounted upon said upright plate and having an opening registering with the opening in said upright plate, a wear plate protecting the lower edge of the opening in the base plate, a bracket mounted upon said upright plate, and a tuyère supported from said bracket, portions of said wear plate and tuyère being approximately in alignment and inclining downwardly and rearwardly relative to said upright plate.

25 2. In a stocker, an upright plate adapted to be secured upon the front wall of a furnace and having a fuel feed opening therein, a base plate mounted upon the front of said upright plate and having an opening registering with the opening in said upright plate, a wear plate protecting the lower edge of the opening in the base plate, a bracket mounted upon the rear of said upright 30 plate, and a tuyère supported from said bracket, portions of said wear plate and tuyère being approximately in alignment and inclining downwardly and rearwardly relative to said upright plate.

35 3. In a stoker, an upright plate having an opening therein, a base plate mounted upon the front of said upright plate and having an opening registering with the opening in the upright plate, an inverted channel-shaped wear plate straddling 40 and protecting the lower edge of the opening in the base plate, a bracket fastened to the rear of said upright plate, and a tuyère supported from said bracket and forming with the same and said upright plate a windbox, portions of said 45 tuyère and wear plate being approximately in alignment and inclining downwardly and rearwardly relative to said upright plate.

40 4. In a stoker, an upright plate having an opening therein, a base plate on the upright plate and having a fuel feed opening registering with the opening in said upright plate, a bracket fastened to the upright plate, a wear plate straddling and protecting an edge of the opening in the base plate, and a tuyère supported from the bracket 55 and having a portion forming a rearward extension from the wear plate.

45 5. In a stoker, a tuyère having a body of metal, and a protecting covering on the underside thereof of high temperature heat resisting cement, the upper portion of the body having a part for attachment to a suitable support and inclining downwardly and rearwardly, the lower portion of 60 said body extending at substantially an acute angle to the upper portion and comprising a

relatively wide upper web, a relatively narrow lower web substantially parallel to said wide web, and an upright web extending between and terminally connected to the wide and narrow webs, the cement aforesaid enveloping and being suspended from the narrow and upright webs, slots for the passage of air being provided in the upper portion of the body, and recesses being provided in the cement for the passage of air.

6. In a stoker, a tuyère having a body of metal, and a protecting covering on the underside thereof of high temperature heat resisting cement, the upper portion of the body having a part for attachment to a suitable support and inclining downwardly and rearwardly, the lower portion of said body extending at substantially an acute angle to the upper portion and being in the form of a relatively wide web, said web being provided at its free end with a depending portion, a relatively narrow web extending from said depending portion in substantially parallel relation to the wide web and then upward to the lower end of the upper portion of the body, and an upright web extending between and terminally connected to the wide and narrow webs, the cement aforesaid enveloping and being suspended from the narrow and upright webs, the lower face of said cement being substantially flush with the lower end of said depending portion and curving upwardly and being substantially flush with the lower end of the upper portion of said body.

7. In a stoker, a tuyère having a body of metal, and a protecting covering on the underside thereof of high temperature heat resisting cement, the upper portion of the body having a part for attachment to a suitable support and inclining downwardly and rearwardly, the lower portion of said body extending at substantially an acute angle to the upper portion and having substantially parallel webs, and an upright web extending between and connected to the parallel webs, the lower of said parallel webs being narrower than the upper, the cement aforesaid enveloping and being suspended from said upright and narrow webs, slots for the passage of air being provided in the upper portion of the body, and recesses being provided in the cement for the passage of air.

8. In a stoker, the combination with an upright plate having a fuel feeding opening therein, of a hollow member detachably secured to said plate beneath said opening having a top portion or apron inclining downwardly and rearwardly therefrom and a lower portion returning approximately to said plate, the space within said hollow member forming an air chamber with a discharge opening at the rear end of said apron, and the lower portion of said hollow member being provided with a heat resisting protecting cover.

9. In a stoker, the combination with an upright plate having a fuel feeding opening therein of a hollow member having a detachable hooked engagement with said plate beneath said opening, said member having an apron portion inclining downwardly and rearwardly from said opening, a lower portion returning approximately to said plate and forming an air chamber between the same and said apron with discharge openings at the rear end of said apron, the lower portion of said hollow member being provided with a protecting cover of heat insulating material.

ROYCE L. BEERS.
